UNITED STATES PATENT OFFICE.

CHARLES L. TAYLOR AND GEORGE A. DAIDY, OF WASHINGTON, DISTRICT OF COLUMBIA.

SUPPORTING AND FASTENING DEVICE FOR COLLARS.

1,128,635.

Specification of Letters Patent. Patented Feb. 16, 1915.

Application filed November 18, 1912. Serial No. 732,027.

To all whom it may concern:

Be it known that we, CHARLES L. TAYLOR and GEORGE A. DAIDY, citizens of the United States, residing at Washington, in the District of Columbia, have invented certain new and useful Improvements in Supporting and Fastening Devices for Collars, of which the following is a specification, reference being had therein to the accompanying drawing.

This invention relates to supporting and fastening devices for collars and has for its primary object the provision of a simple efficient device of the character stated, designed primarily for use in connection with negligée collars of the flexible or unstarched variety. Collars of the style referred to are usually made of a soft material, folded or turned over to provide an innerfold adapted to be secured in the usual way to the collar band of a shirt, and an outer fold adapted to be secured together at the lower meeting edges of the same to maintain the outer fold in flat condition, while accommodating a tie emerging through the opening between the ends of the outer fold and depending above the securing means referred to. These collars being of the soft, flexible nature, as stated, have a tendency to crush, or become wrinkled beneath the chin of the user and in that manner impairs a neat close fitting of the collar.

The characteristic feature of the present invention is the overcoming of the crushing or wrinkling of the collar, and to that end comprises means for normally supporting the collar in its close fitting position on the user while permitting the same to yield or give under depression of the chin, and more specifically said means acting automatically to stretch the collar vertically and thus continually restore the same to a flat neat normal condition.

Another characteristic of the invention resides in the formation of a device possessing the foregoing feature of yieldability, of a wire or similar skeleton formation contoured to conform to the curvature of the neck of the user, lending to the comfort of the latter, while performing its expected supporting function with reference to the collar in connection with which the device is employed.

Other features of the invention comprise means on the supporting device for engag-

ing the upper edges of the outer fold of the collar to maintain the same in a closed condition; means also mounted on the device for engagement with the lower meeting edges of said outer fold; and means between said last mentioned means for engagement with the usual collar button at the front of the neck band of a shirt.

The foregoing and other details in the construction and operation of parts will be apparent from the specific description hereinafter contained when read in connection with the accompanying drawings forming a part hereof and wherein the preferred embodiment of the invention is illustrated.

In the drawings: Figure 1 is a perspective view showing the application of the device to a negligée collar when in use; Fig. 2 is a top plan view of the device detached; Fig. 3 is a front elevation of the device showing in full lines its expansive tendency to render taut the front of the collar, and in dotted lines the capability of the device to spring or bend inwardly under pressure of the chin; Fig. 4 is a view similar to Fig. 3 showing the position assumed by the device when within a collar, the latter being shown in dotted lines, Fig. 5 is an edge view of the device as shown in Fig. 3, and Fig. 6 is an enlarged view looking down upon the upper edge of the device to show the details of the central portion thereof.

Referring more specifically to the drawings wherein like reference letters designate corresponding parts in the several views, and first with reference to Fig. 1, A represents an ordinary negligée collar of soft material, the same having the usual inner and outer folds, the former attached to the collar band of the shirt through the medium of the customary collar buttons, not necessary to herein specifically illustrate, the neck-tie A' passing through the opening between the meeting edges of the outer fold of the collar and the lower meeting edges of the said outer fold being connected together beneath the neck-tie, as at C.

Referring now to the supporting and fastening device more clearly disclosed in the remaining figures of the drawings, it will be seen that the device is of a skeleton or frame-like formation, composed primarily of a single-piece of fine spring wire having a slightly arched top member D, curved transversely in keeping with the usual cur-

vature of the neck of the user, and depending curved converging side members E also curved forwardly to conform to the curvature of the neck, the members D and E being connected together integrally at the corners F, the latter constituting bending points. The upper member D is joined at the middle of the same by a flexible connection G constituted by forming eyes in the 10 terminal portions of the wire and coiling the wire upon itself, as at g, the extremities being turned outwardly approximately parallel to the member D and pointed to constitute opposite inwardly directed prongs 15 g' adapted to catch the inner ply or plies of the outer fold of a collar.

In vertical alinement with the flexible joint G, the lower portion of the wire intermediate of the side members E is bent 20 upwardly to form a downwardly opening loop H adapted to receive the usual front collar button, indicated at h, Fig. 4, and at opposite sides of this looped portion H, spaced at suitable distances apart, the wire 25 is bent to form forwardly projecting stems J, on which buttons K may be formed or affixed as desired, the purpose of these buttons being to engage the button-holes L in the outer fold of the collar A.

30 From the foregoing construction the operation of the device may be readily understood. The inner fold of the flexible collar being buttoned, as usual to the neck band of the shirt, the attachment may be inserted 35 within the space between the folds of the collar, the loop H engaging the front collar button h, and the top member D lying within and against the upper folded or closed edge of the collar. The neck-tie being 40 passed around the collar, the lower meeting edges of the outer fold of the latter may be engaged with the buttons K to hold the flaps of the collar in place behind the tie and the upper meeting edges of the outer 45 fold of the collar may be permanently retained in a neat abutting or closed relation by engaging the prongs g' with the inner ply or plies of the outer fold of the collar, as will be apparent. The springy character 50 of the frame being of a nature to widen somewhat in a vertical direction, enables the compression of the frame when the attachment is inserted in the collar and engaged against downward movement by the 55 collar button h and against upward movement by engagement of the folded edge of the collar,—Fig. 4. By this arrangement the collar is maintained in a taut or smooth, flat condition, notwithstanding its flexibility or soft nature, as hereinabove brought out. The purpose of flexibly connecting the middle portion of the upper member D is to facilitate the bending or downward 60 deflection of the same under pressure of the 65 chin of the user, and to enable prompt

righting of the said member when the pressure of the chin is withdrawn, the natural springy character of the device also assisting in this self-adjusting, so to speak, function of the device. The formation of the 70 device in the open or frame-like manner and of the springy wire also enables a substantial range of adjustment, the side members E being capable of being spread apart or drawn closer together as necessity may require, correspondingly raising and lowering the horizontal member D so that the device 75 may accommodate itself to collars of different heights.

While we have herein disclosed what we 80 believe to be the preferred embodiment of the invention it will be apparent to persons skilled in the art that the invention is capable of embodiment in other forms and devices than that herein presented for the 85 purpose of imparting a full understanding of the invention.

We claim:—

1. A collar support of the character described comprising a frame adapted to be 90 inserted in a collar, said frame comprising a top bar adapted to engage the folded upper edge of the collar, and oppositely projecting prongs on said top bar adapted to stick into the outer folds of the collar to 95 maintain the same in closed position.

2. A collar support of the character described comprising a frame adapted to be inserted in the collar having a yieldable top bar adapted to engage the folded upper 100 edge of the collar, a lower portion adapted to engage a collar button, and separated fastening buttons disposed at opposite sides of the collar-button engaging means.

3. A collar support of the character described comprising a frame adapted to be 105 inserted in the collar having a yieldable top bar adapted to engage the folded upper edge of the collar, a lower portion adapted to engage a collar button, and means adjacent to the collar button engaging means for 110 engaging the flaps of the outer fold of the collar.

4. A collar supporting device of the character described comprising an open frame 115 adapted to be inserted in a collar beneath the folded edge of the same, said frame having a connecting top bar and downwardly converging side bars connected together at their lower ends, securing means carried at 120 said lower ends, the top bar being independent of said means to permit deflection of said top bar without interfering with said means, the top bar being bowed in a forward direction to its point of connection with the side 125 bars, the side bars being bowed forwardly in a similar manner downwardly to the securing means, in combination with means on the top bar for engaging the outer folds of the collar to prevent separation thereof. 130

5. A collar supporting device of the character described comprising a spring wire frame adapted to be inserted in the collar having a pivotally connected top member 5 adapted to engage the folded upper edge of the collar, means at the lower portion of the frame adapted to engage a collar button, and means adjacent to the collar button engaging means adapted to engage the flaps of 10 the outer fold of the collar.
6. A collar supporting device of the character described comprising a spring wire frame adapted to be inserted in the collar having a flexibly connected top member 15 adapted to engage the folded edge of the collar, means at the lower portion of the frame adapted to engage a collar button, and inwardly projecting prongs adapted to catch the outer fold of the collar carried 20 by said top member of the frame.
7. A collar supporting device of the character described comprising a spring wire frame adapted to be inserted in the collar having a flexibly connected top member adapted 25 to engage the folded edge of the collar, means at the lower portion of the frame adapted to engage a collar button, means adjacent to the collar button engaging means adapted to engage the flaps of the outer fold of 30 the collar, and inwardly projecting prongs adapted to engage the outer fold of the collar carried by said top member of the frame.
8. A collar support of the character described comprising a frame adapted to be 35 inserted in a collar, said frame comprising an approximately horizontally disposed elongated top bar adapted to engage the
- folded upper edge of the collar and to lie within said fold, and separated parts on said top bar adapted to fasten into the upper portions of the outer folds of the collar to maintain the same in closed position. 40
9. A collar support of the character described comprising a frame adapted to be inserted in a collar, said frame comprising a top bar adapted to engage the folded upper edge of the collar, separated parts on said top bar adapted to fasten the outer folds of the collar to maintain the same in closed position, and means at the lower portion of the frame adapted to engage the collar button of a shirt. 45
10. A collar support of the character described comprising a frame adapted to be inserted in a collar, said frame comprising a top bar adapted to engage the folded upper edge of the collar, separated parts on said top bar adapted to fasten the outer folds of the collar to maintain the same in closed position, and means at the lower portion of the frame adapted to engage the collar button of a shirt, in combination with other means adjacent to said collar button engaging means adapted to engage the free 50 portions of the outer folds of the collar to maintain the same in closed position. 55
- In testimony whereof we affix our signatures in presence of two witnesses.
